UNITED STATES PATENT OFFICE.

CHRISTIAN WILLIAM MEINECKE, OF JERSEY CITY, NEW JERSEY, ASSIGNOR
TO MEINECKE & CO., OF NEW YORK, N. Y., A CORPORATION OF NEW
JERSEY.

DESIGN FOR AN INVALID-CUSHION.

SPECIFICATION forming part of Design No. 35,497, dated December 31, 1901.

Application filed December 3, 1901. Serial No. 84,578. Term of patent 14 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for an Invalid-Cushion, of which the following is a specification.

My invention relates to a new and original design for cushions used to relieve invalids who are suffering from bed-sores, and is illustrated in the accompanying drawings, in which—

Figure 1 is a plan view. Fig. 2 is a side elevation. Fig. 3 is an end elevation.

The leading feature of my design resides in an oval or oblong opening placed in a square or rectangular cushion.

In said drawings the letter *a* indicates the sides or rectilinear portions of the cushion,

placed at right angles or square to one another. The opening *b* is of oval or oblong shape and is located centrally or with an equal width of cushion at each side of the opening and equal widths of cushion at each end thereof.

The design presents a cushion having a novel, pleasing, and distinguished appearance.

What I claim as new, and desire to secure by Letters Patent, is—

The design for a cushion substantially as herein shown and described.

In testimony whereof I have hereunto set my hand in the presence of two subscribing witnesses.

CHRISTIAN WILLIAM MEINECKE,
Witnesses:

DANIEL HOGAN,
E. F. KASTENHUBER.
